UNITED STATES PATENT OFFICE

2,155,763

LIQUID AND GASEOUS FUEL CARBURETOR

Fred N. Laub, Los Angeles, Calif., assignor to Ensign Carburetor Co., Ltd., Huntington Park, Calif., a corporation of California

Application November 11, 1936, Serial No. 110,241

4 Claims. (CL 261—16)

This invention pertains to carbureting apparatus for internal combustion engines, and has for its general purpose to provide an improved carburetor capable of operating on either liquid or gaseous fuel, and to provide a simple and practical means for adapting various standard or commercial liquid fuel carburetors for operation on gas.

Within recent years the increasing development and manufacture of certain types of normally gaseous fuels have made it advantageous in many instances to use such fuels in preference to other (normally liquid) fuels. This is particularly true as regards the so-called "liquid petroleum gas," recovered by absorption and fractionation from natural gas and consisting of normally gaseous propane and butane, distributed in pressure containers in which the fuel is maintained under liquefying pressure. This fuel is highly satisfactory for the operation of internal combustion engines because of its constituency, and in many instances is preferred because of lower cost and availability. When fed to the carburetor the fuel is in gaseous form, having been vaporized mainly by reducing its pressure, although usually it is subjected to low temperature heating to insure complete vaporization.

Instead of building a carburetor capable of operating on gaseous fuel alone, it is preferable in a great many situations and for apparent reasons, that the carburetor be capable of operating selectively on either type of fuel. Also there is a practical advantage in being able to adapt gasoline carburetors already in use, or gasoline carburetors of standard manufacture, to operate on gaseous fuel. In accordance with the invention, I have provided a simple and generally applicable means of converting standard gasoline carburetors into gas carburetors, but without affecting their utility as such. It will be understood of course that in its broad aspects, the invention is not limited to the adaption of already built carburetors to use gaseous fuel, but also includes all carburetors embodying the combination claimed.

The invention will be more fully explained and understood to best advantage from the following detailed description of a typical and illustrative form of carburetor embodying the invention. Reference is had throughout the description to the accompanying drawings, in which:

Fig. 1 is a general side elevation showing the typical form of carbureting apparatus embodying the invention;

Fig. 2 is a vertical section on line 2—2 of Fig. 1;

Fig. 3 is a horizontal section through the gas nozzle on line 3—3 of Fig. 1; and

Fig. 4 is a fragmentary section showing the normal relationship between certain parts of the gasoline carburetor before insertion of the gas nozzle between the body sections.

In the drawings, I have shown the invention incorporated in a typical and known form of gasoline carburetor, for the purpose of illustrating an embodiment of the general combination, i. e. a combined gasoline and gas carburetor, and also to illustrate the adaptability of the invention to gasoline carburetors in general to equip them for operation on gaseous fuel. While I have shown the gas supply system to be incorporated in a standard and known type of down-draft dual gasoline carburetor, it is to be understood that the invention is also and equally well adaptable to other forms or types of gasoline carburetors, particularly where the bodies are of sectional construction permitting insertion of the gas supply nozzle.

Referring first to Figs. 1 and 2, the gasoline carburetor comprises a body including sections 10, 11 and 12, sections 10 and 11 being connected by screws 13, and sections 11 and 12 normally, that is before insertion of the gas nozzle 14, being held together by screws applied to flanges 11a and 12a. The upper body section 10 forms suction passage inlet 15 and contains the usual choke valve 16 mounted on shaft 17. Below the inlet 15, the suction passage, generally indicated at 18, increases to a maximum cross sectional area at 19 within the upper interior of intermediate body section 11, and below the enlarged section 19, the suction passage is divided into separate parts by the tubular walls or venturis 20 interconnected by a central web 21, see Fig. 3. It may be mentioned that in certain aspects of the invention, the tubular walls 20 may be regarded as forming individual suction passages, bearing in mind that broadly, the invention is not limited to a carburetor of the illustrated dual arrangement.

Gasoline is drawn into the suction passage of the carburetor through nozzles 22 discharging into Venturi tubes 23 positioned in axial alignment with the circular cross sectional passages 20a within tubes 20. As will be apparent, passages 20a serve as mixing passages for combining the relatively rich fuel and air mixture being discharged from the venturis 23, with the main air stream flowing into the upper end of tubes 25.

20 around the venturis 23. It will suffice to state without describing or illustrating in detail all parts of the gasoline carburetor, that the liquid fuel is supplied to nozzles 22 from the usual float 5 chamber 11d contained in the intermediate body section 11. Also that a common type of manual adjustment generally indicated at 25, and as more fully illustrated and explained in my copending application, Ser. No. 102,718, filed September 26, 10 1936, on Carbureting apparatus, may be provided for shutting off the gasoline supply to the carburetor while the latter is operating on gaseous fuel, as hereinafter explained.

Lower body section 12 connected at 26 to the engine manifold inlet 27, contains the usual throttle valves 28 carried on shaft 29, passages 30 being continuations of the mixing or individual suction passages 20a formed within body section 11. Fig. 4 illustrates the normal relationship or relative positions of body sections 11 and 12 of the gasoline carburetor before insertion of the gas supply nozzle 14. The lower portions of tubes 20 normally extend downwardly within passages 30, fitting the bore walls 31 forming these passages. The throttles 28 are operated by rod 33 connected to arm 34 of bell crank 35 carried on the throttle shaft 29, the choke valve 16 also being manually controlled by rod 36 connecting with arm 37 having an operating connection at 38 with arm 39 on the choke shaft 11. The throttle and choke valve mechanisms are interconnected by the usual rod or linkage 40, the purpose and effect of which is known to those familiar with the art and requires no specific explanation. The illustrated type of carburetor also has an accelerating fuel pump lever 41 operatively connected with arm 42 on the throttle shaft by means of rod 43. In the gasoline carburetor, rods 40 and 43 ordinarily are 40 single piece members as shown at 40' and 43' in Fig. 4, and the only purpose of illustrating them herein, is to explain that in order to accommodate the gas nozzle 14, which, when inserted between the body sections, lengthens the distance between the terminal connections with rods 40 and 43, the latter are severed and the sections are connected by splicers 45 and 46 which permit proper adjustment of the rod lengths to correspond with the increased spacing of their terminal connections.

50 The gas supply nozzle 14 is shown typically as comprising a body 48 of uniform thickness inserted between the carburetor sections 11 and 12 and clamped between flanges 11a and 12a by screws 49 passing through holes in the nozzle body as illustrated in Fig. 3. Body 48 contains a gaseous fuel passage 51 to which the gas is supplied through line 52 leading from a pressure regulator conventionally illustrated at 53 in Fig. 1, and operating to deliver gas to the nozzle passage at substantially constant pressure, preferably atmospheric or slightly below atmospheric pressure. A conventional showing of the gas pressure regulator will suffice since such devices per se are well known. The flow of gas through passage 51 may be manually regulated by suitable valve means between the regulator outlet and the carburetor suction passage. Preferably I provide the flow regulating valve in the nozzle itself and show, typically, a longitudinally adjustable valve 54 threaded in the body at 55, the inner cylindric end 54a of the valve extending across the passage bore 51 and within a transverse bore 56 of slightly larger diameter than the 70 valve portion 54a.

Beyond the valve, the gas passage progressively increases in size at 51a toward the outlets 51, the latter being formed by intersecting bores 51a in the bottom wall 48a of the nozzle body. The top wall 48b of the body (see Fig. 2) has corresponding bores 58 in vertical alignment with bores 51 to receive the gasoline carburetor mixing tubes 20. Separate portions of the gas stream are deflected by a vertical web or baffle 60 extending between the top and bottom walls 48b and 48a 10 of the nozzle body, toward the annular outlets 51. The side and end walls 48c and 48d of the nozzle body are spaced from the outside of tubes 20, permitting the gas streams flowing from passages 51a to enter spaces entirely surrounding the tubes except at web 21, and to be drawn through inlets 51a into the suction passage by virtue of the velocity of the air streams leaving the mixing tubes. By providing spaces substantially surrounding the tubes and into which the gas is fed, the gas is caused to flow uniformly around the entire peripheries of the bottom open ends of the tubes, as it is taken into the suction passage.

With the carburetor thus equipped to supply combustible mixtures of gasoline or gas, the engine may be operated selectively on either fuel. When operating on gas supplied through nozzle 14, the gasoline supply to the carburetor will be shut off, and, vice versa, the gas supply will be 30 shut off either by closing valve 54 or some other valve (not shown) in the gas supply system, when the carburetor is operating on gasoline. As will be apparent, the engine may be started using either type of fuel and a change to the other fuel effected while the engine is running. However, the main purpose of providing both liquid and gaseous fuel supply means in a single carburetor, is to render the carburetor capable of operating on either kind of fuel to best suit particular conditions, for example to be able to utilize one fuel where the other may not be available, or where it may be more economical or advantageous to use one instead of the other. While any suitable gaseous fuel may be used, the apparatus has 40 at present its most extensive use in connection with "liquid petroleum gas", as previously mentioned, and which ordinarily will be supplied to the pressure regulator inlet 53 in vaporized or substantially completely vaporized form.

It may be mentioned that the gas nozzle body 48 may in some installations contain liquid fuel passages, depending upon the type and construction of the carburetor in which the nozzle is inserted, to permit normal functioning of the carburetor when operating in liquid fuel. To illustrate, the carburetor is shown in Fig. 1 to have the usual idling by-pass passages 63 and 65, 66 in the walls of body sections 12 and 11, respectively, the discharge of fuel from passages 63 into 60 the suction passages being controllable by needle valves 62. Provision is made for maintaining the continuity of these idling fuel passages after insertion of the gas nozzle by drilling passages 64, see Fig. 3, that register with passages 63 and 65 65 in the carburetor.

I claim:

1. A carburetor having a body comprising a pair of spaced sections containing a suction passage, Venturi means in one of said sections restricting the suction passage, said suction passage being less restricted within the other of said sections, a throttle in the last mentioned section and an outlet beyond the throttle in the direction of air flow through said passage, a tubular suc- 75

- tion passage wall projecting from the end of said Venturi containing section, means for supplying liquid fuel to the suction passage within said Venturi containing section, a gas fuel supply 5 nozzle surrounding said wall and removably inserted between said body sections, said nozzle comprising walls spaced axially of said suction passage wall and forming between them a gas passage, and the suction passage wall forming 10 with the nozzle a gas outlet slot discharging into said suction passage between the Venturi means and the throttle.
2. A carburetor having a body comprising a pair of spaced sections containing a suction passage, Venturi means in one of said sections restricting the suction passage, said suction passage being less restricted within the other of said sections, a throttle in the last mentioned section and an outlet beyond the throttle in the direction of 20 air flow through said passage, a tubular suction passage wall projecting from the end of said Venturi containing section, the throttle containing section having a bore into which said tubular wall may be inserted, means for supplying liquid 25 fuel to the suction passage within said Venturi containing section, a gas fuel supply nozzle surrounding said wall and removably inserted between said body sections, said wall forming with the nozzle a gas outlet slot discharging into 30 said suction passage between the Venturi means and the throttle.
3. A carburetor having a body comprising a pair of spaced sections containing a suction passage, Venturi means in one of said sections restricting the suction passage, said suction passage being less restricted within the other of said sections, a throttle in the last mentioned section and an outlet beyond the throttle in the direction 35
- of air flow through said passage, a pair of tubular suction passage walls projecting from the end of said Venturi containing section, means for supplying liquid fuel to the suction passage within said Venturi containing section, a gas fuel supply nozzle removably inserted between said sections and having a pair of bores surrounding and spaced from said suction passage walls, said nozzle comprising a gas inlet, and walls spaced axially of said suction passage walls and forming 10 between them a gas passage discharging into the spaces between the nozzle and said suction passage walls between the Venturi means and the throttle.
4. A carburetor having a body comprising a 15 pair of spaced sections containing a suction passage, Venturi means in one of said sections restricting the suction passage, said suction passage being less restricted within the other of said sections, a throttle in the last mentioned section 20 and an outlet beyond the throttle in the direction of air flow through said passage, a pair of tubular suction passage walls projecting from the end of said Venturi containing section, means for supplying liquid fuel to the suction passage 25 within said Venturi containing section, a gas fuel supply nozzle removably inserted between said sections and having a pair of bores surrounding and spaced from said suction passage walls, said nozzle comprising a gas inlet, walls spaced axially 30 of said suction passage walls and forming between them a gas passage discharging into the spaces between the nozzle and said suction passage walls and at a point between said Venturi means and the throttle, and means within said gas passage 35 diverting separate portions of the gas stream to said spaces.

FRED N. LAUB.
